CAR RETARDER

George C. Beltman and Donald H. Sweet, Chicago,
Ill.; said Sweet assignor to said Beltman.

Application March 18, 1947, Serial No. 735,315

19 Claims. (Cl. 188—62)

1.

This invention relates to the automatic control of the speed of wheeled vehicles, and more specifically to the automatic retardation of vehicles not otherwise controlled as to speed. It includes among its objects and advantages the automatic reduction of the speed of the wheeled vehicle to a predetermined minimum definitely greater than zero, and finds its chief field of usefulness in railroad classification yards.

In the accompanying drawings:

Figure 1 is a side elevation of a retarder unit according to the invention;

Figure 2 is a plan view of the same;

Figure 3 is an end view of the retarder of Figure 1 as on line 3—3 of Figure 2;

Figure 4 is a side elevation of the cross beam forming a double pivot for the beams of Figure 1;

Figure 5 is an end view of the same beam;

Figure 6 is a section through the dash pot of a retarder, on line 6—6 of Figure 7;

Figure 7 is a section on line 7—7 of Figure 6;

Figure 8 is a partly diagrammatic side elevation of one means for blocking up the beams when desired; and

Figure 9 is a similar view of a modified actuating means.

In the embodiment of the invention selected for illustration, each retarder unit is a pair of short rail sections inserted in both rails side by side. Each insert section includes a long beam 40 and a short beam 42. As best indicated in Figures 1 and 2, the beams 40 and 42 are inserted between lengths of ordinary rail 44 and 46 and constitute a continuation of the rail surface over which the wheels of the car pass. In Figure 1 the contour of the rail surface, hidden by the flanges of the beams, is indicated by the dot and dash line 45. In unloaded position the upper surfaces of the beams 40 and 42 occupy the upper dot and dash line position of Figure 1 and present a short incoming section about 12 inches long sloping upward about an inch to a maximum elevation at 48, and a longer section about 54 inches long. The last six inches is level with the fixed rail 46, and the remainder slopes up to join the short section. The joints between all these sections are notched, as best indicated at 50 in Figure 2, to transfer the wheel more smoothly from one section to the next.

The long beam 40 has a fixed pivot 52 spaced about 6 inches from the fixed rail 46, and supporting hangers 47 formed in the upper flanges 54 of the beam. At the other end, the flanges 54 end in downwardly opening hangers, or hook-shaped end portions 56, which hook-shaped por-

2.

tions overlie the loadbearing upper edge of the carrier cross beam 58. The short beam 42 also has flanges 60 extending throughout its length and terminating in similar hangers 61 symmetrically spaced outside the hangers 56 and riding on the same crossbeam 58. Adjacent the fixed rail 44, the flanges 60 have downwardly facing hangers 51 riding on struts 62 on either side of the rail 44, which struts rest in fixed sockets 63. The flanges 54 and 60 both extend up about one and one-half inches above the rail. This saves weight and also guards against wheels leaving the rail.

The articulate supporting means described permit the beams 40 and 42 to move down to bring the rail surface to the position of the lower dot and dash lines of Figure 1, with the apex 48 about two inches below the level of the rails 44 and 46.

It will be apparent that a wheel moving off the rail 44 and encountering the beams in the lower dot and dash position will be subjected to an accelerating force as it rolls down the beam 42 and to an equal retarding action as it subsequently rolls up along beam 40 so that it will tend to return to the rail 46 with the same speed as it had when it left the rail 44. However, if a wheel encounters the beams in the upper position and rides part or all the way out to the apex 48 while the beams remain substantially in that position, it will not be accelerated. And if the beams are then lowered substantially to the lower position, as by letting the cross beam 58 sink, the sinking will not accelerate the wheel but the subsequent climb up the long beam 40 will retard it.

The cushioning means for the cross beam 58 is both load sensitive and speed sensitive and is best illustrated in detail in Figures 3 to 7. The beam 58 is centrally notched down at the top as at 64 (see Figure 4), to clear the rail portions of the beams 40 and 42. Under each wing it has a downwardly facing abutment surface 66, and projecting downwardly in the middle is a strut 68 entering a dash pot indicated as a whole by the reference character 70.

A piston 72 moves vertically in the cylinder 73, kept filled with liquid up to the level indicated at 74 in Figure 6, as by means of a conventional float valve 71. It has a guiding skirt 76 sliding freely in the cylinder 73, and a plurality of grooves 78 for collecting fluid working up around the skirt, which fluid flows back to the outside through weep holes 79. The top of the piston 72 has an upwardly facing socket 80 receiving the

end of the strut 68. The peripheral wall of the cup contains one or more threaded openings, each receiving a calibrating plug 82, which may be made up with central openings of various sizes. A lifting spring 84 is housed under the piston 72 and abuts the bottom of the dashpot. Air accumulating under the piston can exit through a weep hole 77. The tension of the lifting spring 84 exceeds the weight of the beams 40 and 42 by approximately half of the load carried by one wheel of a light or empty car, when the parts are in elevated position. When the piston is depressed to the bottom of its stroke, the spring load may desirably increase to about $\frac{1}{2}$ or $\frac{3}{4}$ of the load of the wheel of a light car. Suitable means are provided for positively preventing the beams from rising above the full line position of Figure 1, such as bolts 86 anchored in the foundation and engaging the upper surface of the bottom flange 88 of the beam 40. A ring 89, held down by bolts 91, facilitates assembly by carrying the initial tension of the spring 84, when the strut 68 is not effective for that purpose. Check valves 85 operate to let the piston move up with relatively negligible damping action.

It will be apparent that a car wheel rolling along at 12 miles per hour will travel the length of the short beam 42 in approximately $\frac{1}{20}$ of a second and then spend more than $\frac{1}{20}$ of a second passing over the long beam 40, if it does not slow down. But the same wheel rolling along at 2 miles per hour will take six times as long on both beams, spending $\frac{1}{3}$ of a second on the short beam 42 and about $\frac{1}{2}$ of a second on the long beam 40. And to depress the beams to their lowermost position in an 18th of a second will force the liquid in the dash pot to pass through the plug 82 six times as fast as when the displacement takes place in $\frac{1}{3}$ of a second. Accordingly, the resistance of the dash pot to the fast downward movement will be greater than that offered to the slow movement in the ratio of about 36 to 1.

Thus the plug may be calibrated to oppose the fast movement with sufficient force to momentarily carry the load of the wheel to the end of the short beam 42 while only a small fraction of the complete downward displacement has occurred, and the rest of the displacement will take place while the wheel is passing over the initial portions of beam 40. Thus a very light car going 12 miles an hour might pass over the beam 42 while the fulcrum lowers a half inch and the fulcrum would go down another inch and a half as the wheel covered about the first foot of the beam 40. Such a wheel would never have any downhill travel, climbing a slight incline most of the way across the beam 42 and being let down about an additional inch on the beam 40 and required to climb back up again.

But at the same speed a car of maximum weight might push the pivot down an inch and a half by the time it reached the end of the beam 42 and get down the full distance by the time it had covered about six inches of the beam 40. It will be apparent that, traveling at the same speeds, a heavy car will be required to do materially more climbing than a light car so that both will be retarded but the heavy car will be retarded more strongly.

However, when either a heavy car or a light car travels as slowly as two miles an hour across the beam 42, there is ample time for the beams to go to substantially their lowermost position before the wheel has covered more than a frac-

tion of the length of the beam 40. And under such circumstances substantially the entire effect on the wheel will be to let it roll downhill and then uphill to the same vertical displacement without material retardation. And at all intermediate speeds throughout the range, the timing of the dash pot action will make it effective to exert a retarding action substantially proportional to the square of the speed of the car.

Cut-out controls

After a train has been assembled, it is customary to go into the yard with a locomotive and bring the train out at the same end where it was put in. An ideal installation might be provided with trackage at the other end to take the trains out, but in any practical installation it will be necessary to bring the cars back out at the same end occasionally, and in present yards that is common practice. When a train is being taken out over the gravity retarders, it is undesirable to have either the locomotive or the cars operate the gravity retarders although, at reasonable speeds not exceeding 15 miles an hour, the main effect would be only to jounce the cars up and down a little.

Referring to Figures 1 and 8, the abutments 66 of the cross beam 58, when the parts are in elevated position, are spaced three inches from foundation abutments indicated in Figure 1 at 98, which abutments function as a stop to limit the downward movement. A blocking yoke is provided comprising end blocks 92 and a cross reach 94 curved back to allow clearance for the strut 68. The yoke is normally held in the position of Figure 1 by light tension springs 95. The blocks 92 are two inches high, and may be drawn across under the abutment faces 66 so that downward movement of the beams is limited to a position where they present a level track. The parts may be drawn into blocking position by a pair of tension rods 96.

Means are provided for actuating the tension rods 96 in two different ways. An automatic actuating means is illustrated in Figure 8 and includes a plate 98 about 36" long, lying beside the wheel-carrying surface and extending on both sides of the pivot 52. The plate is held in the position of Figure 8 by a pair of compression springs 100, one at each end, encircling guiding bolts 102. The guiding bolts pass through stationary guide blocks 104 apertured to leave substantial clearance around the bolts to permit free movement of the plate. Washers 106 held in place by nuts 108 limit upward movement of the bolts 102. A bell crank lever 110 is pivoted at 112 and has one arm underlying the left hand bolt 102 and a vertical arm apertured to receive a tension rod 114 loosely. Springs 116 and abutments 118 on the rod 114 provide a resilient lost-motion connection between the bell crank 110 and the tension rod 114. The other end of the tension rod connects with the upper end of a vertical catch lever 120 having a hook 122 movable to catch under the corner of a housing 124 on the right hand bolt 102. The pivot 126 for the catch-rod 120 is carried by a horizontal arm 127 on a shaft 128. The shaft 128 has a downwardly extending arm 130 receiving the tension rod 96 loosely. The tension rod has abutments 132 at its end and springs 134 between the abutment and the arm 130, which springs are two or three times as stiff as the springs 95 pulling on the yoke 94 in the other direction.

It is apparent that a wheel coming from the left as viewed in Figure 8 will first depress the left end of the plate 98, which will fulcrum around the right end abutment 104. This downward movement will rock the bell crank lever 110 and pull on the tension member 114 and swing the catch lever over under the housing 124. This condition will continue while the wheel continues to the middle of the plate 98 and the housing 124 is also pushed down, rotating the shaft 128 and arm 130 in a clockwise direction and pulling the yoke and the blocks 92 between the abutment faces 56 and the abutments 90. As the wheel continues over the beam 40, it will impose the load of the wheel on the beam and on the abutment faces 66 so that by the time the wheel leaves the plate 98 the blocks 92 are firmly gripped by the weight of the wheel passing over, and remain in that condition until the wheel leaves the beam 42. In the meantime, the parts have returned to the initial position so that as soon as the spring 84 begins to lift the beams back up, the yoke 94 and blocks 92 can move back to the position of Figure 1 under the unopposed force of the springs 95.

It is also apparent that a wheel traveling in the other direction, after it has traversed both beams, either with or without being retarded thereby, will depress first the right hand end of plate 98 and then the left hand end. The first depression will move the housing 124 down below the hook 122 and the second depression will merely compress one of the springs 116 a little and cause the toe of the hook 122 to press lightly against the housing 124. But nothing will happen to the blocks 92, so that a following wheel on the same truck or another car coupled to the car which has just passed will find the entire device ready to function and effect whatever retardation the speed and load of the next wheel calls for.

Referring to Figure 8, I have indicated a stringer, or pipe, 138, which may be connected to the ends of the depending levers 130 of a plurality of gravity retarders by means of drag cords 140. This permits an engineer taking an empty locomotive in either direction over a series of gravity retarders to stop and lock all retarders in inoperative position and restore them to operative condition after he has passed over them, by manually displacing the stringer 38 to the left.

Figure 9 illustrates a simplified linkage for operating the blocks 92. The swinging control lever 142 normally occupies the full line position of Figure 9, being held in contact with pivot 144 by light springs 146 strong enough to carry the weight of the lever and associated parts. The upper end of the lever projects about 2" above the rail level, in the plane of the wheel flanges, and carries a contact roller 148 to engage the wheel flanges. In the full line position, the fixed pivot 144 lies in the lower apex of a V-shaped slot 143 in the lever 142. It will be apparent that the initial contact of a wheel coming from the left and engaging the roller 148 will tend to push the lever down until the pin 144 reaches the end of the left arm of the V, after which further movement will carry the roller 148 down to the right and act through the springs 150 to pull on the tension member 96.

However, a wheel coming from the opposite direction will tilt the lever 142 in a counterclockwise direction, which will either do nothing to the blocks 92 or will push them a little further

out of blocking position. With the modification of Figure 9 it is necessary to connect the lever 142 through flexible tension cords 152 so that the automatic operation is not interfered with by the connection for manual operation.

Retarders of the conventional side friction type are insensitive to both speed and load. They can do more retarding in a given distance than gravity retarders according to the invention, but because the friction depends on the condition of the side surfaces of the wheels, it is out of the question to secure uniform or precise results with them. However, a side friction retarder need only get the incoming cars down to anything between about five and about twelve miles per hour, and gravity retarders can finish the job with precision.

A complete new installation with gravity retarders may advantageously employ a hump of materially reduced height, and do all the retarding by gravity. This does away with many maintenance problems. In such an installation the retarders on the hump and in the switching section need to be set for much higher speeds.

Others may readily adapt the invention for use under various conditions of service by employing one or more of the novel features disclosed, or equivalents thereof. For instance, in gravity retarders for high speed operation on the hump, it will be advantageous to increase the length of the beam 42 by from 50% to 100%, and in any gravity retarder that will be called on to move its plunger down with more than half the acceleration of gravity, hangers on the cross beam should be connected to the cross beam, to follow it down without separation.

The preferred fluid for the dash pot is primarily water, but in climates where freezing temperatures are experienced, the water should be protected by a conventional anti-freeze compound, preferably one with a higher boiling point than water, such as diethylene glycol. When a yard is active, the energy absorbed by the dash pots will keep the contents boiling hot and evaporate substantial quantities of water. But each heat increment will appear in the body of liquid at a point outside the cylinder where the liquid jet issues from the cylinder, so that it will not be difficult to make the reservoir surrounding the cylinder of adequate area for steam liberation.

As at present advised with respect to the apparent scope of our invention, we desire to claim the following subject matter:

55. 1. In a railroad car retarder, in combination: spaced fixed rail sections positioned with a gap between them; two longitudinally aligned beams, together bridging said gap; the one of said beams at the end identified as the entrance end being shorter than the other; a common pivotal support for the adjacent ends of said beams; individual pivotal supports for the remote ends of said beams; said individual supports being positioned to hold the remote ends of said beams substantially level with the adjacent track; said joint pivotal connection being vertically movable; hydraulic dashpot means connected to said joint pivotal connection and adapted to absorb a maximum amount of energy during downward movement and a relatively negligible amount of energy during upward movement; spring means biasing said joint pivotal connection upwardly; and stop means limiting the action of said spring means to a position in which the parts are posi-

tioned for a full downward stroke of said dashpot.

2. In a railroad car retarder, in combination: spaced fixed rail sections positioned with a gap between them; two longitudinally aligned beams, together bridging said gap; a common pivotal support for the adjacent ends of said beams; means for guiding said joint pivotal connection in movement in a predetermined path between an upper position and a lower position; hydraulic dashpot means connected to said joint pivotal connection and adapted to absorb a maximum amount of energy during downward movement and a relatively negligible amount of energy during upward movement; spring means biasing said joint pivotal connection upwardly; and stop means limiting the action of said spring means to a position spaced from said lower position.

3. In a railroad car retarder, in combination: spaced fixed rail sections positioned with a gap between them; two longitudinally aligned beams, together bridging said gap; pivotal supporting means for the adjacent ends of said beams; said pivotal supporting means guiding said adjacent ends in movement in a predetermined path between an upper and a lower position; hydraulic dashpot means connected to said supporting means and adapted to absorb a relatively large amount of energy during downward movement and a relatively small amount of energy during upward movement; and means biasing said supporting means upwardly toward said upper position.

4. In an automatic railroad car retarder, in combination: spaced fixed rail sections positioned with a gap between them; a plurality of vertically movable sections articulated to each other and to said fixed rail sections to receive and support the entire weight of a car wheel to be retarded; hydraulic dash pot means underlying and connected to certain of said movable sections; said dash pot means having a permanently open vent and another vent provided with an inwardly opening check valve; and resilient means biasing said sections upwardly when not under load; said permanently open vent being small enough to cause said dash pot to temporarily support the entire weight of a car wheel moving at a speed in excess of three miles per hour.

5. In an automatic railroad car retarder, in combination: spaced fixed rail sections positioned with a gap between them; and a plurality of vertically movable sections articulated to each other and to said fixed rail sections to receive and support the entire weight of a car wheel to be retarded; hydraulic dash pot means connected to certain of said movable sections; said dash pot means having a permanently open vent and another vent provided with an inwardly opening check valve; and resilient means biasing said sections upwardly when not under load; said permanently open vent being small enough to cause said dash pot means to temporarily support the entire weight of a car wheel moving at a speed in excess of a predetermined maximum safe coasting speed at which a car can be stopped by impact with standing cars without injury to the contents of the car.

6. In an automatic railroad car retarder, in combination: a plurality of vertically movable rail sections articulated to each other and positioned to receive and support the entire weight of a car wheel to be retarded; hydraulic dash pot means connected to certain of said movable

sections; said dash pot means having a vent; and resilient means biasing said sections upwardly when not under load; said vent being small enough to cause said dash pot to temporarily support the entire weight of a car wheel moving at a speed in excess of a predetermined maximum safe coasting speed at which the contents of the car will remain undamaged by stoppage of the car by impact with other cars standing still on the same track.

7. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; said absorbing means being adapted to resist downward movement with a variable force approximately proportional to a higher power, not less than about the square, of the speed of the downward movement.

8. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; said absorbing means being adapted to resist downward movement with a variable force approximately proportional to a higher power, not less than about the square, of the speed of the downward movement; said absorbing means comprising a hydraulic dashpot.

9. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a

predetermined maximum; and means for absorbing and dissipating energy in retarding the downward movement of said inlet end.

10. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; said absorbing means being adapted to resist downward movement with a variable force approximately proportional to a higher power, not less than about the square, of the speed of the downward movement; said absorbing means comprising a hydraulic dashpot; the entering end of said section being normally materially above the fixed rail surface and movable from its uppermost position downwardly below said rail surface.

11. A track retarder for railroad rolling stock comprising, in combination: a first track section, identified as a receiving section, supported at a substantially constant level at one end, identified as the receiving end; a second relatively long track section adjacent said first section and identified as a delivery section; said delivery section having a delivery end remote from said receiving section supported at a substantially constant level; said receiving and delivery sections having their proximate ends in substantial abutment; said proximate ends being articulated together about a common axis; resilient means normally supporting said common axis in position to hold the proximate ends of said sections a predetermined distance above a straight line joining the remote ends of said sections; stop means limiting upward movement of said axis; stop means limiting the downward movement of said axis to a bottom position spaced below a straight line joining the ends of said sections by a distance about twice as great as the upward deviation in the uppermost position of said axis; and damping means resisting downward displacement of said axis; said damping means for absorbing and dissipating energy in resisting downward displacement of said axis, said damping means operating hydraulically to oppose downward movement of said axis with a force approximately proportional to a higher power, not less than two, of the speed of downward movement; said means for limiting downward displacement of said axis including a fixed abutment and a co-operative abutment movable downward with said axis; means for raising the effective level of said fixed abutment to limit downward movement of said axis to a position where said sections are in a straight line, said raising means comprising a movable block adapted to be interposed between said abutments when they are sufficiently separated; manual means for moving said raising means into operative position; and automatic means rendered operative by entry of a wheel traveling in reverse direction, for moving said raising means into operative position; said automatic means including a movable

element adjacent the delivery end of said long section and positioned to be displaced in one sense by a wheel moving in one direction and in an opposite sense by a wheel moving in the opposite direction; and a connection for actuating said raising means upon displacement of said movable element in one sense, but not by displacement in the opposite sense.

12. A track retarder for railroad rolling stock comprising, in combination: a first track section identified as a receiving section supported at a substantially constant level at one end, identified as the receiving end; a second relatively long track section adjacent said first section and identified as a delivery section; said delivery section having a delivery end remote from said receiving section supported at a substantially constant level; said receiving and delivery sections having their proximate ends in substantial abutment; said proximate ends being articulated together about a common axis; resilient means normally supporting said common axis in position to hold the proximate ends of said sections a predetermined distance above a straight line joining the remote ends of said sections; stop means limiting upward movement of said axis; stop means limiting the downward movement of said axis to a bottom position spaced below a straight line joining the ends of said sections by a distance about twice as great as the upward deviation in the uppermost position of said axis; and damping means resisting downward displacement of said axis; said damping means for absorbing and dissipating energy in operating hydraulically to oppose downward movement of said axis with a force approximately proportional to a higher power, not less than two, of the speed of downward movement; said means for limiting downward displacement of said axis including a fixed abutment and a co-operative abutment movable downward with said axis; means for raising the effective level of said fixed abutment to limit downward movement of said axis to a position where said sections are in a straight line; and automatic means including a movable element adjacent the delivery end of said long section and positioned to be displaced in one sense by a wheel moving in one direction and in an opposite sense by a wheel moving in the opposite direction; and a connection for actuating said raising means upon displacement of said movable element in one sense but not by displacement in the opposite sense.

13. A track retarder for wheeled vehicles comprising, in combination: two adjacent track sections having their proximate ends in substantial abutment and vertically movable; the remote ends of said sections being supported at substantially constant level; resilient means normally supporting said proximate ends in a predetermined elevated position when not under load; stop means positively limiting the downward movement of said proximate ends; and damping means for absorbing and dissipating energy during downward displacement of said proximate ends, but not during upward return to said predetermined elevated position.

14. In an automatic railroad car retarder, in combination: a vertically movable rail section positioned to receive and support the entire weight of a car wheel to be retarded; hydraulic dashpot means connected to said section; said dashpot means having a vent; and resilient means biasing said section upwardly when not under load; said vent being small enough to

cause said dashpot to temporarily support the entire weight of a car wheel moving at a speed in excess of a predetermined maximum safe coasting speed.

15. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; said absorbing means being adapted to resist downward movement with a variable force approximately proportional to a higher power, not less than about the square, of the speed of the downward movement; said absorbing means comprising a hydraulic dashpot; the entering end of said section being normally materially above the fixed rail surface and movable from its uppermost position downwardly below said rail surface; said movable section being combined with another movable section adjacent its entering end; said sections being articulated at their remote ends at the level of the adjacent fixed surfaces; said sections being articulated to each other at their proximate ends.

16. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; said absorbing means being adapted to resist downward movement with a variable force approximately proportional to a higher power, not less than about the square, of the speed of the downward movement; said absorbing means comprising a hydraulic dashpot; the entering end of said section being normally materially above the fixed rail surface and movable from its uppermost position downwardly below said rail surface; said movable section being combined with another movable section adjacent its entering end; said sections being articulated at their remote ends at the level of the adjacent fixed surfaces; said sections being articulated to each other at their proximate ends; said means for dissipating energy being a hydraulic dashpot connected to the proximate ends of said portions.

17. Equipment for automatically controlling the speed of a railroad car traveling on conventional rails, comprising, in combination with a fixed rail surface: a movable section interpolated in the rail surface; said section having an entrance end and an exit end; means for supporting the exit end of said section at all times substantially level with the continuation of said rail surface; the entering end of said section being vertically movable and normally at a predetermined level with respect to the adjacent fixed rail surface; means supporting said section in undisturbed position with a force materially less than the weight normally imposed on said section by a car wheel; stop means limiting the downward movement of the inlet end of said section to a predetermined maximum; and means for absorbing and dissipating energy in retarding the downward movement of said inlet end; 10 said absorbing means being adapted to resist downward movement with a variable force approximately proportional to a higher power, not less than about the square, of the speed of the downward movement; said absorbing means comprising a hydraulic dashpot; the entering end of said section being normally materially above the fixed rail surface and movable from its uppermost position downwardly below said rail surface; said movable section being combined with another movable section adjacent its entering end; said sections being articulated at their remote ends at the level of the adjacent fixed surfaces; said sections being articulated to each other at their proximate ends; said means for dissipating energy being a hydraulic dashpot connected to the proximate ends of said portions; the articulation of the exit end of said long portion being fixed; the other two articulations permitting slight longitudinal movement to 20 compensate for the angularity of said portions.

18. A track retarder for wheeled vehicles comprising, in combination: two adjacent track sections having their proximate ends in substantial abutment and vertically movable; the remote ends of said sections being supported at substantially constant level; resilient means normally supporting said proximate ends in a predetermined elevated position when not under load; stop means positively limiting the downward movement of said proximate ends; damping means for absorbing and dissipating energy during downward displacement of said proximate ends, but not during upward return to said predetermined elevated position; said stop means comprising a fixed abutment and a co-operating abutment movable downward with said proximate ends; and means for changing the effective level of said fixed abutment to limit downward movement of said axis to a bottom position at a higher level; said means comprising a movable block adapted to be interposed between said abutments when they are sufficiently separated. 25

19. A track retarder for wheeled vehicles comprising, in combination: two adjacent track sections having their proximate ends in substantial abutment and vertically movable; the remote ends of said sections being supported at substantially constant level; resilient means normally supporting said proximate ends in a predetermined elevated position when not under load; stop means positively limiting the downward movement of said proximate ends; damping means for absorbing and dissipating energy during downward displacement of said proximate ends, but not during upward return to said pre- 30

determined elevated position; said stop means comprising a fixed abutment and a co-operating abutment movable downward with said proximate ends; means for changing the effective level of said fixed abutment to limit downward movement of said axis to a bottom position at a higher level; said means comprising a movable block adapted to be interposed between said abutments when they are sufficiently separated; normally inoperative automatic means for interposing said block between said abutments; and connections actuated only by a wheel moving in one predetermined direction, for rendering said automatic means operative.
